(57) CLAIM

The ornamental design for a hat, as shown and described.

DESCRIPTION

FIG. 1 is an enlarged perspective view of a hat showing my new design;

FIG. 2 is a top view thereof;

FIG. 3 is a bottom view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines showing in each of the Figures represent stitching that forms a part of the claimed design.
